MUSICAL TOTE BOX OR THE LIKE

Ernest L. Thornell, Horicon, Wis., assignor to Marlin
Toy Products, Inc., Horicon, Wis.

Filed Mar. 2, 1970, Ser. No. 21,680

Term of patent 14 years

Int. Cl. D3—99

U.S. Cl. D87—1

FIG. 1 is a perspective view of a musical tote box or the like embodying my new and ornamental design;

FIG. 2 is a side elevation of the same;

FIG. 3 is a perspective view of the same shown in opened condition.

I claim:

The ornamental design for a musical tote box or the like, as shown.
